FIRE POT BLOCK

Frank R. Higley, Cleveland Heights, Ohio, assignor to The Bryant Heater Company, Cleveland, Ohio, a corporation of Ohio

Application July 4, 1942, Serial No. 449,743

2 Claims. (Cl. 126—151)

This invention relates to improvements in fire pot blocks, primarily blocks for fire pots of the magazine type for heating furnaces or stoves intended for the burning of solid fuel. Reference may be had to a copending application of Eric H. Ryden and myself, Serial No. 449,744, filed July 4, 1942, for an adaptation of such a fire pot to a heating furnace.

One of the objects of the present invention is the provision of a fire pot block of such character that when a multiplicity of such blocks are assembled to make up a fire pot or fire pot lining, passages for air and gases are provided and evenly distributed along the interior walls of the fire pot.

Another object is the formation of these passages in such manner that they will not be clogged by pulverulent material such as slack, sawdust, granule distillery by-products, etc., or the ashes present at the bottom of the fire pot.

Still another object is the provision of blocks for a furnace fire pot of the magazine type adapted to provide quick acceleration of the rate of combustion after a prolonged low combustion rate, for example, in order to bring about quick heating in the morning after the fire has been banked all night.

Other objects and features of novelty will appear as I proceed with the description of that embodiment of the invention which, for the purposes of the present application, I have illustrated in the accompanying drawing in which

Fig. 1 is a front elevational view of a block which may be employed as one of a series of identical elements of a cylindrical fire pot embodying the invention;

Figs. 2 and 3 are top and bottom plan views respectively, of the same;

Fig. 4 is a side view looking in the direction of arrows 4—4 of Fig. 2;

Fig. 5 is a cross-sectional view taken substantially on the line 5—5 of Fig. 2;

Fig. 6 is a vertical sectional view of a portion of a hot top lining assembled from blocks like that illustrated in Figs. 1 to 5 inclusive, the view being taken substantially on the line 6—6 of Fig. 7;

Fig. 7 is a plan view of a fragment of an assembled lining employing the blocks of the invention, and

Fig. 8 is an elevational view of the construction shown in Fig. 4.

The front surface of each block has deformations therein providing a single overhang and a plurality of complementary cavities, the sides of

the overhang being inclined so that fluid passages are provided extending from the bottom of a course of blocks to the top thereof. The overhangs in a given course recur regularly and are staggered with respect to those of adjacent courses, so that a fluid passage along the surface of one block is continued along the surfaces of blocks in the courses next above and below. The upper surface of a groove or cavity must have an inclination less than the angle of repose of any pulverulent material which may be contained in the fire pot, for example, slack or ash.

In the invention as herein illustrated the horizontal dimension of the block is greater than the vertical one. As shown, each block of a course occupies a sector of 60°, thereby requiring six blocks for a course.

The metal shell in which the blocks are mounted is indicated at 12'. Each block has outer wall portions 30 near its sides, which are contoured to fit the cylindrical shell 12', and intermediate portions 30 there is a flat outer portion 31 extending from top to bottom of the block and providing a vertical passage 32 between the block and shell. Each of the passages 32 is connected with corresponding passages of the next adjacent blocks by horizontal passages 33 through the bottom of the outer wall portions 30. Passages 33 and 32 may be used as check draft passages for distributing air around the circumference of the fire pot and introducing it into the furnace dome rather than into the draft pipe, all as more particularly described in the copending application above referred to.

The side walls 34 of the blocks conform with radial planes through the axis of the fire pot. Hence the last block of a course functions as a key to lock all of the blocks of that course in position.

The upper and lower surfaces 35 and 36 of each block are flat and parallel, being perpendicular to the axis of the fire pot. The front or inner face of the block is deformed to provide in this instance a single overhang which includes a narrow strip 36' that is part of the lower surface of the block, and triangular surfaces 37 which diverge laterally away from the strip 36' and which have the minimum amount of draft necessary to permit the casting of the block. The angle with the horizontal made by the surfaces 37 is less than the angle of repose of the pulverulent material to be handled, in order to prevent the filling up of the overhung cavities along the sides 37 of the overhang.

At the middle of the front surface of the block

there is a ridge 38. From this ridge and from the forward edge of the top surface 35 the front faces 39 of the overhang slope downwardly and outwardly until they meet the surfaces 37 or the side walls 34 of the block. The lower end of the ridge 38, which is the high spot of the front face, 5 may be flattened to produce a small triangular surface 40.

Two blocks of each of two different courses are illustrated in Fig. 7 in assembled relation. It 10 will be noted that the blocks of one course are staggered with respect to those of the next course. Thereby the central part of the overhang of each block stands directly above the joint between two blocks of the course next beneath. This is of 15 some importance inasmuch as the joints may not fit perfectly in all cases, and if they were not staggered but were in vertical alignment some leakage of pulverulent material might occur through a joint into the cavity below the overhang. In other words there might be occasional 20 stoppage of the passage at the joints between blocks.

It may be noted also that since the flat rear surface 31 of a given block overlaps the similar surfaces of the blocks next above and below, a series of small vertical passages 41 between the lining and the shell 12' are provided, extending from top to bottom of the fire pot.

In Fig. 6 I have indicated by the broken line 42 the angle of repose considered radially of pulverulent material in the fire pot. Directly beneath the strip 36' constituting the middle part of the overhang a cavity 43 results which is open for the passage of air and/or unburnt gases and products of combustion. The blocks beneath the overhang constitute the inner wall of this cavity, but it continues up along both sides of the overhang between the surfaces 37 and triangular surfaces 44. These cavities continue in decreasing cross-section toward the upper and outer corners of the triangular surfaces 37 and 44. Considerably before a given cavity to one side of an overhang runs out, however, it communicates with a cavity formed by an overhang of a block in the course next above, so that a substantially continuous passage is provided from one cavity to the next. These passages are inclined and they may be considered to define helical paths from the bottom to the top of the fire pot. There are two sets of such helical paths inclined in opposite directions, providing both right-hand and left-hand threads. These crossed passages define in addition zigzag paths from the bottom to the top of the fire pot, and it is these zigzag paths which are ordinarily utilized primarily, I believe, as draft passages for the air and gases.

Considered with respect to the radial distance from the shell 12', the single high point of this block is the small triangular surface 40. There are four low points marked "L" in the drawing, and three intermediate points marked "I." All of the low points are positioned at the same radial distance from the axis of the fire pot and all of the intermediate points have another like dimension. When the blocks are assembled into a lining, intermediate points at the adjacent ends of two blocks come into registration with the intermediate point at the middle of the block next beneath. Likewise, the two low points at the middle of one block come into registration

with the low points at the adjacent ends of the two blocks next beneath. The blocks are so designed also that the intermediate points I of a given block are in the same plane with the triangular high spot 40, this plane being parallel to the plane of the surface 31 at the back of the block. This is of some importance because it reduces to a minimum the voids in the block, and thereby gives maximum strength and reduced die cost. The location of the intermediate points at the ends of the block in the same plane with the high spot 40 also facilitates packaging of the block.

The location of the high spot 40 and the ridge 15 38 at the middle of the block is of advantage because it places the maximum thickness dimension at the middle where the strain is greatest. When coking occurs and causes expansion in the 20 fuel bed, heavy pressures are exerted radially outward on the various blocks. The maximum thickness dimension at the center therefore assists the block to withstand this strain.

The die which is employed for molding the 25 front face of the block must, of course, be withdrawn by movement in a direction normal to the back surface 31. The triangular surfaces 37 are parallel to this direction of movement except for the minimum necessary draft, but with respect to 30 axial planes, in which the pulverulent material flows primarily, the surfaces 37 incline upwardly to an increasing extent toward the outer extremities of those surfaces, thereby increasing the cross-sectional area of the cavities or passages 35 toward their outer ends over what those areas would be if the intersections of the surface 37 with all axial planes remained horizontal lines. This condition will be apparent from an inspection of Fig. 5, where the cavity is marked 43'.

The block herein disclosed may be used in 40 either an up draft or a down draft furnace, it being essential merely that the draft passages extend throughout the length of the fire pot from bottom to top thereof.

Having thus described my invention, I claim: 45 1. A block for building up the lining of a fire pot, having front and back walls, top and bottom walls and two side walls, said front wall having a high spot overhang at the lower end of its mid-section and having low spots at its upper corners 50 and spots of the same intermediate height at its lower corners and the upper end of its mid-section, whereby when a series of blocks are assembled in staggered relation the low spots come under the overhangs and the points of intermediate height come together, forming a pattern of substantially diamond shaped areas with their high spots at the bottom corners and low spots at the other three corners.

2. A refractory block for use in building up the 60 lining of a cylindrical fire pot, said block having side walls conforming with radial planes through the axis of the fire pot, an overhang at the lower end of the mid-section of the front face of the block, the side surfaces of said overhang diverging upwardly toward the side walls of the block and lying in planes substantially perpendicular to the vertical plane through the chord of the arc subtended by the block, whereby radial planes to 65 either side of the median axial plane will define undercuts beneath said overhang.

FRANK R. HIGLEY.
